UNITED STATES PATENT OFFICE.

FREDRICK W. WOOD, OF NORWICH, CONNECTICUT, AND JOHN F. BINGHAM,
OF LAWRENCE, MASSACHUSETTS.

HANDLE FOR UTENSILS.

SPECIFICATION forming part of Letters Patent No. 487,688, dated December 6, 1892.

Application filed September 9, 1892. Serial No. 445,467. (No model.)

To all whom it may concern:

Be it known that we, FREDRICK W. WOOD, of Norwich, in the county of New London, State of Connecticut, and JOHN F. BINGHAM, of Lawrence, in the county of Essex, State of Massachusetts, have invented certain new and useful Improvements in Handles for Utensils, of which the following is a description sufficiently full, clear, and exact to enable any person skilled in the art or science to which said invention appertains to make and use the same, reference being had to the accompanying drawings, forming part of this specification, in which—

15 Figure 1 is a side elevation of our improved handle; Fig. 2, an edge elevation of the same, the utensil being represented as broken away; Fig. 3, a central section through the bail-ear; Fig. 4, an elevation of the outer side of the 20 bail-ear, and Fig. 5 a horizontal section taken on line $\alpha\alpha$ in Fig. 4.

Like letters of reference indicate corresponding parts in the different figures of the drawings.

25 Our invention relates especially to an improved method of pivoting the handles of tea-kettles, pots, and similar utensils, whereby sufficient tension is imparted to retain the handle in an assumed position; and it consists in certain novel features hereinafter fully set forth and claimed, the object being to produce a simpler, cheaper, and more effective device of this character than is now in ordinary use.

35 The nature and operation of the improvement will be readily understood by all conversant with such matters from the following explanation.

In the drawings, A represents the kettle, 40 and B the bail or handle. Bail-ears d are secured to the kettle in the usual manner and the bow-shaped bail B is pivoted thereto by pivot-pins f . An annular groove m (shown in Figs. 4 and 5) is formed in the bail-ears.

45 The bail is provided with the usual wooden or insulating handle proper g . On the pivot-pin we mount a metallic cap h , which has a slot at i to astride the bail, whereby said cap is rotated with said pin as the bail is moved.

50 The edge of the cap rests in the groove m , as

shown in Fig. 5. The pin being headed against the cap, the edge of said cap at j , opposite the slot i , is forced tightly against the face of the bail-ear, affording a frictional tension for the handle. This tension is sufficiently great to 55 enable the handle to be adjusted at various angles in relation to the utensil and hold it in such position, as illustrated by dotted lines in Fig. 2. To guard against the handle proper g falling onto the body of the utensil and becoming charred or heated thereby, we form two bosses or projections k on the outer face of the bail. (See Figs. 1 and 2.) At the inner edge of the cap h , adjacent its slot i , we form a projection p , which will engage one of said 65 bosses when the handle is turned downward in either direction and serve as a stop to support said handle in the position illustrated by dotted lines, preventing the handle proper from coming into contact with the utensil- 70 body. Instead of said bosses or projections, an inwardly-projecting lip t (see Fig. 5) may be formed on the bail-ear, which projects into the path of the bail and will support the same out of contact with the utensil. The cap h also 75 serves as a finish to cover the connection of the bail and ears. The tension of the cap against the bail is ordinarily sufficient to effect all of the results described, and as an additional precaution we provide the stop-bosses m and k and 80 lip t . By forming the groove m as a guide for the cap the bail-ear is rendered more rigid and the strain by the use of the cap in said groove on the pivot is greatly relieved.

Having thus explained our invention, what 85 we claim is—

1. The combination, with a kettle or similar utensil, of bail-ears thereon, a bail pivoted to said ears, and a cap mounted on said pivot and slotted to astride said bail, the opposite 90 edge of said cap being in frictional contact with the face of said bail-ear, substantially as and for the purpose set forth.

2. The bail-ear and bail pivoted thereto, in combination with the metallic cap h , mounted 95 on the bail-pivot and indented at i to receive said bail, all being arranged to operate substantially as described.

3. The combination, with a kettle or similar utensil, of bail-ears secured thereon and 100

provided in their faces with an annular groove, a bail pivoted to said ears, and a cap mounted on said pivot and slotted to astride said bail, the edge of said cap being disposed in the bail-ear grooves, substantially as described.

4. The combination, with the bail-ear provided with the annular groove *m* and a lip *t*, of the bail pivoted to said ear and a cap *h* on the bail, pivoted and slotted to astride said bail

and having its edge working in said groove, said cap being movable by said bail, substantially as described.

FREDRICK W. WOOD.
JOHN F. BINGHAM.
